CLAIM

The ornamental design for a mobile communication device, as shown and described.

DESCRIPTION

FIG. 1 is a perspective view of a mobile communication device showing our new design in a tilt state.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is another perspective view thereof in an open state; and,

FIG. 9 is still another perspective view thereof in a close state. The broken lines immediately adjacent the shaded areas represent the bounds of the claimed design while all other broken lines are directed to environment and are for illustrative purposes only; the broken lines form no part of the claimed design.
